UNITED STATES PATENT OFFICE.

DICK B. WILLIAMS, OF NEW ORLEANS, LOUISIANA, ASSIGNOR TO L. FRANK & COMPANY, OF NEW ORLEANS, LOUISIANA, A COPARTNERSHIP COMPOSED OF LEON FRANK AND LEONARD HOCHSTEIN.

DESIGN FOR AN AUTOMOBILE-SIGNAL.

50,411.

Specification for Design.

Patented Feb. 27, 1917.

Application filed December 13, 1916. Serial No. 136,798. Term of patent 14 years.

To all whom it may concern:

Be it known that I, DICK B. WILLIAMS, a citizen of the United States, residing at New Orleans, in the parish of Orleans and State of Louisiana, have invented a new, original, and ornamental Design for Automobile-Signals, of which the following is a specification, reference being had to the accompanying drawing, forming part thereof.

Figure 1 is a perspective view of an automobile signal showing my new design.

Fig. 2 is a front elevation thereof.

I claim:

The ornamental design for an automobile signal as shown.

DICK B. WILLIAMS.

Witnesses:

EDITH WITKOFF,
RALPH BAN.
